UNITED STATES PATENT OFFICE.

ALBERT RUSH, OF COLUMBUS, OHIO, ASSIGNOR TO THE VANCE COMPANY, OF COLUMBUS, OHIO, A CORPORATION OF OHIO.

MEANS FOR OPERATING ELEVATOR-DOORS.

1,372,090.

Specification of Letters Patent. Patented Mar. 22, 1921.

Application filed June 21, 1919. Serial No. 305,888.

To all whom it may concern:

Be it known that I, ALBERT RUSH, a citizen of the United States, residing at Columbus, in the county of Franklin and State of Ohio, have invented a certain new and useful Improvement in Means for Operating Elevator-Doors, of which the following is a specification.

The object of this invention is to provide improved means for operating a door and more especially a door that is installed at the elevator shaft or well and is adapted to be raised and lowered to open and close the entrance to the elevator carriage.

The invention is embodied in the example herein shown and described the features of novelty being finally claimed.

In the accompanying drawings—

Figure 1 is a side view with the door and other parts in vertical section and broken out showing the door installed and partially raised in its guiding frame at the well and the carriage equipped with means for operating the door.

Fig. 2 is a front detail view on a larger scale of the devices on the door and the means carried by the carriage for engaging the door devices for operating the door.

Fig. 3 is a side view of what is shown in Fig. 2 with some parts in section.

Fig. 4 is a horizontal section on the line IV—IV Fig. 2 looking down.

Fig. 5 is a front elevation of the door and its equipment including counterweighting means.

Fig. 6 is a diagram illustrating the wiring.

In the views 10 designates the vertical guiding channels for the door, said channels being installed in the building at the opposite sides of the entrance or doorway to the elevator well. 11 designates the door which, in the instance shown, is of special construction designed by me and has rollers 12 mounted on stud shafts 12^a at the opposite corners of its lower end to travel in said channels 10, and rollers 13 at its opposite upper corners to travel in inclined channels 14 mounted on the roof of the car or carriage 15.

In practice the door is normally in lowered position with the upper rollers standing in the upper portion of the channel 10, said rollers standing above the lower arms 55 of members 16 to bridge the gaps between

the channels 10 and the channels 14. The bridging members 16 afford tracks for the rollers 13 when the door is raised to be supported by the channels 14 on the roof of the car. In practice each floor of the building 60 is equipped with a door way and door like that described. Preferably also each door is equipped with counterweights 17 and chains 18 connected therewith, the latter passing over sheaves 19 and connected with 65 the lower opposite corners of the door (see Fig. 5). The car, of course, is equipped with ordinary or suitable means (not shown) for raising and lowering it and for stopping it at any of the several floors. 70

The means for operating the door includes, on the door, brackets or frames 20 hung at their upper ends on the stud shafts 12^a, said brackets being provided at their lower ends with rollers 21 traveling on the 75 door frame to support said bracket in vertical position. The mounting of the brackets 20 on the stud shafts 12^a is loose to permit face-wise oscillation of the door with reference to the brackets. The brackets 20 are 80 conveniently formed somewhat of S-shape in horizontal cross-section, as best seen in Fig. 4, so that one bend shall reach around the wall of channel 10 and the other may form a seat to receive a gripper bar 22. 85 The gripper bar which has toothed or roughened sides is secured in said seat.

The means for operating the door includes also on the car an electric motor hung under the floor of the car and a vertically arranged 90 endless belt or chain 23 driven at the proper time by said motor, said chain passing over a suitable adjustable sprocket wheel 24 mounted in a suitable frame in the upper portion of the car. The frame carrying the 95 sprocket wheel 24 has suitable means 25 for adjusting it vertically to take up slack in the chain.

The chain 23 has connected with or included in it a frame 26 carrying a solenoid 100 27 so that the separate armatures 28 and 29 thereof are pulled toward each other when the solenoid is energized. Pivoted on the frame 26 are clutch members 30 and 31 that are operated by means of pins 32 and 33 105 projecting laterally from head pieces on the outer ends of the armatures and through slots 34 and 35 respectively in the frame and engaging corresponding arms of the clutch members. The other arms of the clutch 110

members are connected by a coil spring 36 so that when the solenoid is not energized the clutch members are held in horizontal or normal position. The engaging portions 5 of the clutch members 30 and 31 project from their carrying levers so as to stand on opposite sides of the gripper bar 22, said engaging members having toothed or roughened faces to engage the corresponding faces 10 of the gripper bar when the solenoid is energized. Any suitable wiring may be employed for conducting electricity for the operation of the motor and the solenoid. The wiring can also include suitable circuit 15 breakers actuated by the door or belt or part thereon for automatically breaking the electric current through the solenoid as the door approaches or arrives at the limit of its travel in each direction. Such circuit 20 breakers in their general characters are well understood by those skilled in the art. I show, however, in Fig. 6 a special system of electrical wiring in connection with the mechanism adapted for operating the door 25 in this instance which will be understood by those skilled in the art. Upon said diagram the clutches shown in the other views are illustrated at 30 and 31. The several parts 30 constituting the system are named on the drawing and the corresponding circuits or lines are designated by corresponding letters. The operating current is introduced at the "service switch" and the current for actuating and reversing the motor is controlled by the "double throw switch." The 35 part marked "limit device" cuts out the current at the two limits of travel. The function of the hatchway limit switches is to throw in and out the resistance of the motor rheostat for the purpose of permitting the 40 diminishing of the speed of the motor at both limits of travel as well as for furnishing starting resistance to the motor. These 45 hatchway limit switches are actuated by suitable projections.

In practice to raise the door the solenoids are energized to grip the bars 22 and the motor operated in the proper direction to cause the upward movement of said bars and the door. To lower the door the solenoid is energized and the operation of the motor reversed to cause the downward movement of the door. As the door must be left in closed position the clutch and operating mechanism are always left in proper position for actuating another door when the car is brought thereto.

The mechanism can be used for operating a door other than the variety herein particularly shown.

The forms of the parts are susceptible of modification without departing from the gist of the invention as claimed.

What I claim is:

1. Means for operating a vertically moving door for an elevator shaft or well including, in combination, a motor on the elevator car, an endless belt driven by said motor, an electro-magnetically operated clutch member on said belt, and stationary 65 means on the door to be engaged by said clutch member.

2. Means for operating a vertically moving door for an elevator shaft or well including, in combination, a motor on the elevator car, an endless belt driven by said motor, a clutch lever carried by said belt and having an engaging surface at its end, a solenoid and armature for actuating said clutch lever, and a stationary grip bar on 75 the door to be engaged by said clutch lever.

3. Means for operating a door for an elevator shaft or well including, in combination, a motor on the elevator car, an endless belt driven by said motor, a clutch lever carried by said belt and having an engaging surface at each of its ends, a solenoid and armature for actuating said clutch lever, and a grip bar on the door to be engaged by 85 said clutch lever.

4. Means for operating a door for an elevator shaft or well including, in combination, a motor on the elevator car, an endless belt driven by said motor, a pair of clutch levers carried by said belt and having engaging surfaces at their ends, a solenoid and armatures actuated thereby for moving 95 said clutch levers into operative position and spring means for holding said clutch levers in inoperative position.

5. In combination with a vertically moving door, a frame pivotally connected with the door and carrying a gripper bar, an elevator car carrying a motor, a vertically traveling belt adapted to be driven by said motor in opposite directions and electro-magnetically operated clutching means carried by said belt, said clutching means adapted to be engaged with and disengaged from said gripper bar.

6. Means for operating a door for an elevator shaft or well, including, in combination, a motor on the elevator car, an endless belt driven by said motor, means for operatively connecting said belt with the door to 115 open and close the same and electrically operated means for automatically releasing said connecting means at each limit of the movement of the belt.

ALBERT RUSH.
